REFRIGERATING SYSTEM AND APPARATUS THEREFOR

Application filed March 26, 1930. Serial No. 439,006.

This invention relates to improvements in refrigerating systems and apparatus therefor. More especially it has to do with a novel heat absorber or evaporator with improved 5 automatic means controlling the quantity of liquid refrigerant available for evaporation.

In the art of refrigeration the absorption of heat is usually accomplished by the conversion of a liquid refrigerant to the gaseous state. It has been the custom to use a refrigerant which boils or evaporates at a relatively low temperature and this has made it necessary to subject the refrigerant while gaseous, at ordinary room temperatures, to rather high 15 pressure and condense it to liquid. This pressure increase naturally raises the boiling point of the liquid and heretofore it has been deemed essential to feed this high pressure liquid to the evaporator through a form of 20 reducing valve in order to reduce its pressure and thus bring its boiling point again within the range of temperatures at which the cooling effect is to be accomplished.

In pursuance of this accepted practice the 25 feed of the liquid refrigerant is usually controlled manually by means of a hand operated needle valve or automatically by means of a diaphragm valve which responds to pressure generated by the sensible heat of the 30 refrigerant gas after leaving the evaporator. If the rate of supply of liquid to the evaporator is constant, as when a hand valve is set for what is deemed to be the proper rate, one of two undesirable conditions inevitably result. If the available heat evaporates the 35 liquid faster than it is supplied, its level in the evaporator rapidly falls and greatly reduces the effectiveness of the unit. If the liquid feed exceeds the amount necessary to 40 absorb the available heat, then some of the liquid passes on into the accumulator, floods the latter and passes thence to the compressor with obviously dangerous results. In the case of the diaphragm valve control, the sensible heat of the evaporated liquid after leaving the evaporator acts upon a separate body of liquid, usually anhydrous ammonia, confined in an auxiliary system of which the diaphragm valve constitutes a part. As this 45 separated body of ammonia is expanded or

contracted in accordance with the variation of temperature of the refrigerant gas of the main system, the diaphragm valve is opened or closed to vary the flow of liquid to the evaporator. It is evident that this method 55 of control depends primarily upon the sensible heat or temperature of the gas leaving the evaporator. If the heat taken up by the refrigerant is merely sufficient to evaporate the liquid, that is to meet the latent heat 60 demand, it follows that the temperature of the gas is substantially that of the liquid refrigerant. Under such conditions the liquid in the evaporator may be largely converted 65 into gas without the temperature or sensible heat of the latter being raised sufficiently to affect an opening of the diaphragm valve. It is only when the evaporated liquid, that is the gas, is itself raised in temperature that any effect is experienced on the auxiliary body 70 of anhydrous ammonia controlling the diaphragm valve. Consequently there is a very appreciable lag between the change in quantity of liquid in the evaporator and the operation of the diaphragm valve to admit more 75 liquid. The result is similar when the control operates to close the diaphragm valve, the liquid in the evaporator may be oversupplied before the temperature of the gas affecting the auxiliary ammonia brings about 80 a closing action of the diaphragm valve. Moreover the employment of the diaphragm valve controlled as above described, requires the addition of other means to entirely cut off the liquid supply to the evaporator upon 85 a stoppage of the compressor, for if the circulation of the refrigerant continues from the high pressure condenser its sensible heat rapidly increases and effects a further opening 90 of the diaphragm valve with resulting flooding of the evaporator, accumulator and feed lines to the compressor. It may be said that in practice, instead of maintaining a desired quantity of liquid ammonia in the evaporator, the quantity of liquid available 95 for absorption of heat has been a variable one. In consequence of this it has been thought necessary to provide evaporators of rather large liquid-holding capacity in the expectation that with a large amount of liquid 100

at hand in the evaporator the heat to be absorbed could be taken up without too great a reduction of the liquid refrigerant. Such practice has led to costly installations which, particularly in respect to the evaporator, occupy a large space and involve numerous pipe and fitting connections with consequent danger of leakage of the refrigerant. In fact, only in recent years has the art developed to the extent that refrigerating systems have been sufficiently reduced in size to be applicable to domestic use.

The present invention is directed to the provision of a novel heat absorber or evaporator which can be made small enough for the ordinary house refrigerator or large enough to take care of the cooling rooms in cold storage establishments or the requirements of ice-making plants, and which in intermediate sizes is adaptable to meet the needs of jobbers and retailers in respect to storage spaces, show cases, and the like. The evaporator constructed in accordance with the principles of this invention is so small in size compared with the amount of heat it is capable of absorbing that the heretofore used methods of supplying liquid to it are quite inadequate, and so a further feature of the invention is to provide means for controlling the supply of liquid to the evaporator to the end that at least a minimum quantity of liquid refrigerant will be ever present for heat absorption. Although particularly designed to meet the demands of the novel evaporator of this invention, the improved control means are nevertheless applicable to other forms of evaporators.

In the accompanying drawings are disclosed illustrative embodiments of the invention. The novel evaporator comprises top and bottom headers and a series of vertical tubes extending between them provided with heat gathering fins. In the case of direct cooling, as where the evaporator is exposed directly to the atmosphere of the room or space to be cooled, there is a power driven fan provided close by the tubes to force the air past them, while in the case of indirect cooling, as when another medium such as brine is cooled by the evaporator and then in turn is utilized to absorb heat where the ultimate cooling is desired, there are provided suitable propulsion means for rapidly moving the said medium past the tubes.

This feature of forced circulation of the air or other medium together with the heat gathering surfaces of the fins, makes it highly essential that the evaporator be amply supplied with liquid refrigerant as otherwise the maximum absorptive capacity of the evaporator can not be realized. Accordingly, there is provided in combination with the evaporator a novel form of control means which insures that the level of liquid refrigerant will not fall below a predetermined

minimum. These means comprise a device, here shown in the form of a float, which responds to changes in level of the liquid refrigerant and actuates other means which govern a valve in the supply line. This valve is located outside the cooled area where it is free from any danger of freezing, and is operated from a source of power whose application may be effected by the remote control means of this invention. As will more particularly hereinafter appear, it is not necessary in connection with the type of control here disclosed to concern oneself with the restriction of the supply passage as has heretofore been customary. On the contrary it is an advantage of the present invention to have the supply valve open quickly and widely enough to very promptly raise the level of the liquid in the evaporator. Furthermore, when this level has been raised it is also desirable to close the valve quickly and with pronounced force, in order that the closure may be complete and not at all susceptible to the leakage which so often attends the generally used types of reduction valves. Thus it is clear that the supply of liquid refrigerant is controlled solely in accordance with the change of liquid level in the evaporator and without regard to the pressure existing in the evaporator or the temperature of the gas beyond it. In short, it is one of the purposes of the invention to provide means actuated in accordance with the level of the liquid in the evaporator to control the supply, to the end that the said operating level will be maintained at all times. It is a feature of the invention that a system embodying its principles of control can be applied to either direct or indirect cooling systems, and to new or existing installations. It is also a feature that by employing the control devices which characterize this invention, other more or less complicated and delicately operated devices and apparatus can be dispensed with, albeit the desired control is actually accomplished.

It is intended that the patent shall cover by suitable expression in the appended claims whatever features of patentable novelty exist in the invention disclosed.

In the accompanying drawings:

Figure 1 is an elevation of a refrigerating system embodying the present invention;

Figure 2 is a front elevation of the evaporator and associated control device;

Figure 7 is a perspective of the moving parts of the float actuated switch.

5 Referring to the drawings, and particularly to Figure 1, the refrigerating system disclosed comprises a compressor 10 adapted to deliver a gaseous refrigerant at high pressure to a condenser 12 wherein the refrigerant assumes the liquid state. From this condenser the liquid flows through feed pipe 14, strainer 16 and a control valve 18 into a casing 20 which, as here shown, serves as an accumulator. From this the liquid 10 continues downward through pipe 22 to the bottom header 24 of an evaporator 26 from which header a series of tubes 28 extend vertically upward to a top header 30. As will later more particularly appear, the liquid refrigerant in the tubes 28 takes up heat which boils the liquid into a gas that bubbles upward through the tubes into the top header 30 and passes thence by a suitable connection into the casing 20. This gaseous refrigerant is then 15 drawn through pipe 32 back to the compressor to begin again its cycle of travel and transformation. The compressor 10 is driven by an electric motor 34 receiving power from the wires 36 and 38. One of these wires is 20 connected with the thermostatic switch 40 which operates at predetermined temperatures in the cooled room 42 to stop and start the motor 34. As will later be made clear, when the thermostat operates to stop motor 34 it also effects control of the liquid supply valve 18 to the extent of preventing said valve from being open while the compressor is idle.

Although the evaporator disclosed is of 25 novel design, it is nevertheless to be taken as representative of any type of evaporator which may be exposed to direct contact with the atmosphere in an enclosed space to be cooled or which may be located in a tank to cool another liquid which in turn is circulated through the region where the ultimate cooling effect is desired. The evaporator herein shown is an extraordinarily compact and highly efficient one. The tubes 28 are preferably expanded in the header plates 24a and 30a, and are arranged in rows across the evaporator, the tubes in adjacent rows being staggered. (See Figure 5.) Each tube is provided with a multiplicity of fins 28a which surround the tube and greatly augment the heat gathering surfaces of the latter. When the evaporator is to be used for cooling an atmosphere there is mounted, on supporting members 44 attached to the bottom plate 24a and the side plates 46, a motor 48 which drives a fan 50 arranged behind and close by the tubes. A series of adjustable louvers 52 are provided across the front of the evaporator for deflecting the cooled currents in an upward direction. If the evapor-

ator is to be employed for cooling another liquid, as for example brine in an ice-making plant, the motor, fan and louvers may easily be removed and other suitable means provided for circulating the brine past the tubes. 70

The staggered arrangement of the tubes causes the propelled medium which is to be cooled to pass with gentle deflections through the evaporator and thus insures that all of it will during its passage through the unit 75 come in direct contact with one or more of the heat gathering surfaces provided both by the tubes and the fins. Because of this and because of the rapid and forced circulation of the said medium, there is an extremely 80 large transfer of heat to the liquid refrigerant in the tubes. This makes it most essential that the tubes be maintained full of the liquid, since the effectiveness of the evaporator is primarily dependent upon the transformation of the refrigerant from the liquid to the gaseous state. The invention enables 85 this desired condition to be realized.

The casing 20 is so positioned with respect to the upper header 30 that when the latter is partly filled with liquid the former will also contain liquid at the same level, here represented by the dotted line 54a in Figure 4. The connection between the top header 30 and the casing 20 is above this level and, as 90 here shown, comprises a flanged outlet 30b on the header and a complementary flanged inlet 20a on the casing. Within the latter, and extending somewhat into the chamber of the casing is a nozzle 56 with opening 95 directed downward, so that in the event of any liquid particles being entrained in the gas passing from the header to the casing, they will be deflected downward into the body of liquid in the casing and not be carried on 100 with the gas through pipe 32 to the compressor.

The casing 20 is generally of cylindrical shape with one end closed by a deformed plate 58. This plate has an integral cylindrical offset 58a which constitutes the bearing of a shaft 60 to the side of which is attached the stem 62 of a float 64. The latter is within the casing 20 and rises and falls in accordance with the change in level of the liquid therein, which as before stated is also the level of the liquid refrigerant in the evaporator. A reduced portion 60a of shaft 60 extends through a suitable stuffing box nut 66 and carries at its end a tube 68 containing mercury. This tube is provided near one end with the terminals of two wires 70 and 72 which form parts of a shunt circuit from the main circuit wires 36—38. The wire 70 leads from wire 36 to the tube 68 and wire 72 leads from the tube to the control valve 18. The shunt circuit is completed by the wire 74 which leads from the valve 18 to the other main wire 38. The tube is arranged cross-wise on the end of shaft 60 and is adjustable 110 115 120 125 130 135 140 145 150

to accommodate any desired range of levels. When set it is so positioned that when the liquid in casing 20 is at the level 54a and the float correspondingly raised to the position shown, the mercury is at the end of the tube remote from the wires 70 and 72, but when the liquid drops to level 54 and the float is likewise lowered, the mercury is at the opposite end of the tube and completes the circuit between these wires. While the specific form of float and electric switch disclosed have been found to be extremely satisfactory, it is to be understood that other means might be provided which are responsive to change in level of the liquid and which would effect the operation of other agencies employing either electrical, pneumatic or hydraulic power.

The completion of the circuit through wires 70 and 72 effects the opening of the control valve 18 assuming the thermostatic switch 40 to be closed. The valve illustrated is of the solenoid type which is commercially available but other suitable types of valves may be employed which are adapted to be opened and closed automatically by the application of electric, pneumatic or hydraulic power. It is a feature of the invention, however, that this control valve need not be restrictive in character but may open wide and close tight, without regard to the fact that the liquid on its approach side is at a much higher pressure than the liquid on its delivery side. Any flash gas which may be generated by the sudden change of pressure in the liquid as it passes the valve simply enters the casing 20 and bubbles to its top. The sudden and complete opening of the valve enables the liquid to rise rapidly in the casing 20 (as well as in the evaporator) to level 54a, thereby lifting the float so as to tip the tube 68 and break the circuit of wires 70, 72. The valve 18 thereupon closes and this closure may, like its opening, be quick and forceful, thus assuring a tight seating of the valve with no danger of leakage such as usually follows when valves of the reducing type are used in refrigerating systems.

Since the level of the liquid in the casing 20 is that of the liquid in the evaporator 26 it is evident that the latter will be always supplied with liquid up to the desired point and thus its most effective performance be assured. Although the evaporation takes place rapidly, with consequent generation of pressure above the liquid in the evaporator, this pressure is also imposed upon the liquid in the float chamber so that the level therein changes precisely in accordance with the change of level in the evaporator and regardless of pressure conditions. Since the liquid can rise no higher than the predetermined level, there is no need of any trap beyond the casing 20 and the line to the compressor can be a simple pipe 32. Such drops of liquid

as may be entrained by the gas flowing through the connection 30b are directed downward by the nozzle 56 and thus do not continue on with the gas into pipe 32.

The evaporator and its associated control means can be made in any size desired to meet the demands of the space wherein cooling is to be effected. It is illustrated as suspended from the ceiling of a room 42 by hangers 76, but the relative sizes of this room and the evaporator are quite out of proportion as a unit of the size depicted will handle a space many times larger than that represented by the room in the drawings. If the space to be cooled contains an unusual amount of moisture, such as at times to cause a frosting of the fins and tubes, the compressor can be stopped by manual adjustment of the thermostatic switch 40. When this switch is open, there is no energy in wires 70, 72 since the latter are shunted from the main wires 36, 38 and consequently the valve 18 will close since it is of the type to spring shut when its coil is disengaged. The fan 50 preferably runs continuously, so that with the compressor idle and the valve 18 closed, the air continues to be circulated through the evaporator. This forced circulation of the air completely defrosts the evaporator in a very short period. Such drainage of moisture as occurs from the evaporator is caught by the drip pan 78 and carried away by the drain pipe 80.

As shown the wires 82, 84 leading to the fan motor 48 are attached to a hand switch 86, having three sets of terminals. Two of these are connected by wires 88, 90 with the main wires 36, 38 ahead of the thermostatic switch 40. With the hand switch thrown as shown in Figure 1, the fan operates continuously. If the switch is thrown downward so as to connect wires 82 and 84 with wires 92 and 94, then the fan will also be controlled by the thermostatic switch 40, since the wire 94 is connected to wire 38 beyond said switch.

I claim:—

1. Apparatus for a refrigerating system, comprising an evaporator having bottom and top headers and a series of tubes extending vertically therebetween, combined with a casing connected to said bottom header for transfer of liquid refrigerant thereto and connected to said top header for transfer of gaseous refrigerant therefrom; means for supplying liquid refrigerant to said casing; and means connected with the casing above the liquid therein for withdrawing gaseous refrigerant therefrom; there being a nozzle associated with the connection between said top header and casing having its outlet opening downward in said casing whereby any liquid entrained in the gaseous refrigerant passing into said casing is prevented from going on with the gas to said withdrawing means.

2. A refrigerating system comprising, in combination, an evaporator having bottom and top headers and a series of vertical ducts extending therebetween; means for circulating the medium to be cooled past said ducts; 5 a casing connected to said bottom header for transfer of a liquid refrigerant and to said top header for transfer of the refrigerant in gaseous condition, said casing being arranged with respect to the evaporator so that the level of liquid in the casing and evaporator correspond; a supply line connected to said casing for supplying the liquid refrigerant thereto and thereby to the evaporator; 10 an electrically operated valve in said supply line; a discharge line connected with said casing for withdrawal of gaseous refrigerant; a float in said casing actuated by the changes of liquid level therein; a shaft actuated by 15 said float; a bulb containing mercury attached to said shaft and arranged to be tilted by the movements of said shaft occasioned by the movements of said float; electric conductors connecting said bulb and said valve, having 20 open ends within said bulb adapted to be electrically connected by the mercury upon the bulb being tilted to a predetermined position; and a source of electrical power connected to said conductors whereby upon the 25 ends of said conductors being connected by the mercury, the said valve is caused to open and thereby admit liquid refrigerant to said casing.

3. A refrigerating system comprising, in combination, an evaporator having bottom and top headers and a series of vertical ducts extending therebetween; means for circulating the medium to be cooled past said ducts; a casing connected to said bottom header for 35 transfer of a liquid refrigerant and to said top header for transfer of the refrigerant in gaseous condition, said casing being arranged with respect to the evaporator so that the level of liquid in the casing and evaporator 40 correspond; a supply line connected to said casing for supplying the liquid refrigerant thereto and thereby to the evaporator; a power operated valve in said supply line; a discharge line connected with said casing 45 for withdrawal of gaseous refrigerant; a float in said casing actuated by the changes of liquid level therein; a shaft connected to said float so as to be oscillated by the movements of said float; a power control device attached 50 to said shaft exteriorly of the casing; a source of power; and connections between said device and said valve and said source of power, whereby upon the said device being moved to a predetermined position by the oscillation of 55 said shaft, the said power is applied to effect opening of the supply valve.

Signed at Providence, Rhode Island, this 22nd day of March, 1930.

/ CHARLES H. BREIDENTHAL.
